DESIGN FOR A COMBINED COMPACT, MATCH HOLDER, AND LIPSTICK HOLDER

Emanuel P. Consiglio, Inglewood, Calif.

Application February 4, 1946, Serial No. 126,237

Term of patent 7 years

(Cl. D86—10)

To all whom it may concern:

Be it known that I, Emanuel P. Consiglio, a citizen of the United States, residing at Inglewood, in the county of Los Angeles and State of California, have invented a new, original, and ornamental Design for a Combined Compact, Matchholder, and Lipstick Holder, of which the following is a specification, reference being had to the accompanying drawing, forming part thereof.

Fig. 1 is an elevational view of one side of a combined compact, matchholder and lipstick holder, showing my new design, in closed position;

Fig. 2 is an edge view thereof;

Fig. 3 is a view of the side opposite that shown in Fig. 1;

Figs. 4, 5, and 6 are views corresponding to Figs. 1, 2, and 3 respectively, with both lids in open position; and

Fig. 7 is a rear end view thereof.

I claim:

The ornamental design for a combined compact, matchholder and lipstick holder, substantially as shown.

EMANUEL P. CONSIGLIO.
